(57) **CLAIM**

The ornamental design for a fanciful lighting device, as shown and described.

DESCRIPTION

FIG. 1 is a perspective view of the lighting device;

FIG. 2 is a front elevation view thereof;

FIG. 3 is a right side elevation view thereof;

FIG. 4 is a left side elevation view thereof;

FIG. 5 is a rear elevation view thereof;

FIG. 6 is a top plan view thereof; and,

FIG. 7 is a bottom plan view thereof.

The broken lines represent portions of the fanciful lighting device that form no part of the claimed design. The stippled-shaded areas in the drawings represent a color contrast, and forms part of the design.
